DIAL REMOTE CONTROL SYSTEM

Jesse S. Le Grand, Nutley, N. J., assignor to
Federal Telephone and Radio Corporation, New
York, N. Y., a corporation of Delaware

Application November 21, 1945, Serial No. 630,067

7 Claims. (CL 318—21)

1

This invention relates to a control system of the type in which electrical pulses are employed to control a remote device.

An object of the present invention is the provision of an improved remote control system.

Another object is the provision of an improved control system in which the position of a continuously rotatable member as for example, a "wafer" type electric switch, or other instrument, is remotely controlled by pulse means, particularly one employing only a single line and return connection.

Another object is the provision of a remote control system wherein the control instrument is a modified form of the rotatable dial switch used in automatic telephone systems and wherein the dial has positions corresponding to the positions of the governed instrument and actuation of the dial from any of said positions to the finger stop will cause pulses to be transmitted to the governed instrument to move the governed instrument to the corresponding position and in which the stop is caused to move in response to the pulses transmitted.

Another object of the present invention is the provision of an improved rotatable dial instrument for producing pulses, and particularly one adapted for use in a remote control system.

Other and further objects of the present invention will become apparent and the invention will be best understood from the following description of an embodiment thereof, reference being had to the drawings, in which the figure is a schematic diagram of a remote control system embodying my invention.

In the system illustrated, there are for example, twelve positions 1-12, of the dial 13 forming part of the dial or governing instrument 14, and the governed instrument 15, which may be of the continuously-rotating type of wafer switch, likewise has twelve corresponding positions, 1' through 12', to which the switch shaft 16 may be turned in response to the operation of the governing or dial instrument 14. The labeled positions of the dial 13 are visible through openings 17 in the dial and are made on a fixed portion of the dial instrument 14. The number of dialing holes 17 is equal to the number of positions of the wafer switch 15, with the dialing holes 17 and the positions of the wafer switch having the same angular separation. The dial 13 is self-returning and is adapted to be manually rotated in a counter-clockwise direction, returning in a clockwise direction and during the course of its return, producing pulses whose number depends

upon the amount it has been manually rotated in a counter-clockwise direction. Thus for example, if the dial has been rotated through three positions, it will produce three pulses as it returns to rest. The dial instrument 14 in this respect is similar to the conventional automatic dial telephone although there is no lift-hook switch and no microphone or receiver. The method of producing pulses by the rotation of the dial may be similar. The pulses are produced by the opening and closing of a switch 18. Unlike the conventional dial instrument, the dial instrument 14 has a movable stop 19 arranged adjacent the periphery of the dial and adapted to engage the finger to prevent it from going beyond the stop. The stop is adapted to rotate into various different positions around the periphery of dial 13 between two adjacent numbers as for example, as indicated between 3 and 4; 5 and 6, etc. The finger stop 19 is adapted to be moved in only one direction which is clockwise, and opposite the direction in which the dial 13 is rotated.

A stepping relay 20 is used to move the finger stop 19 in a circle around the periphery of dial 13. As a pulse of energy is applied to the stepping relay, it moves the finger stop one position as for example, from a position between 3 and 4 to a position between 4 and 5. For each pulse received, the stepping relay will move the finger stop the equivalent of one position and in the embodiment illustrated, it would require twelve pulses to move the finger stop completely around the dial back to its original position. The stepping relay 20 is connected to rotate the dial by suitable mechanical means such as links, etc., shown schematically and designated by the numeral 21.

A similar stepping relay 22 is employed to rotate the shaft 16 of the switch 15, the stepping relay 22 rotating the shaft 16 in a clockwise direction one position for each pulse. The magnetic coils of stepping relays 20 and 22 are connected in series with switch 18 in the dial instrument 14 and in series with a source of power 23 by means of only a single line 24 and return 25.

The operation of the system is as follows. Assuming that the switch 15 is at position 12', the stop 19 will be in a position between 11 and 12 of the dial 13. If position 4 were dialed, the dial being moved counterclockwise, the dial would be permitted to rotate four positions before the stop was reached. Upon release, four pulses would be fed to each of the stepping relays, thus rotating switch 15 to position 4', and the finger stop to a position just between 3 and 4, as illustrated.

If position 9 were now dialed, it would be possible to rotate the dial five positions before the stop was reached. Upon release, five pulses would be fed to each of the stepping relays, thus moving the switch 15 to position 9' and the stop to rest between positions 8 and 9. If position 8 were now dialed, it would be possible to rotate the dial eleven positions counter-clockwise before the stop was reached. Upon release, eleven pulses would be fed to each stepping relay, thus moving the switch 15 to position 8' and the stop to rest between positions 7 and 8.

Thus it will be seen that by inserting the finger in any hole of the dial and rotating the dial up to the finger stop, the governed instrument or switch 15 will be moved into a position corresponding to the number of the hole. Thus the position of the stop on the dial also indicates the position of the governed instrument.

While I have described the details of one embodiment of my invention, it will be apparent that numerous changes may be made in these details. For example, as many positions as desired may be employed instead of the twelve here illustrated. The governed instrument may be other than a switch, and as many governed instruments as desired may be controlled by a single governing instrument. Other pulse-responsive means than the stepping relays may be employed for actuation of the finger-stop moving means and the governed instrument.

Accordingly, while I have described above the principles of my invention in connection with specific apparatus, it is to be clearly understood that this description is made only by way of example and not as a limitation on the scope of my invention as defined in the accompanying claims.

I claim:

1. A pulse-generating dial instrument comprising a manually-rotatable dial, means responsive to the rotation of said dial for producing pulses, the number of pulses produced depending upon the degree of rotation of said dial, a movable finger stop arranged adjacent one position on the periphery of said dial and adapted to stop the finger rotating the dial from passing said position, and pulse-responsive means for moving said finger stop to different positions about the periphery of the dial in accordance with the number of pulses received thereby.

2. A pulse-generating instrument according to claim 1 further including means for transmitting pulses from said pulse-producing means to said finger-stop moving means.

3. A pulse-generating dial instrument compris-

ing a manually-rotatable dial, means responsive to the rotation of said dial for producing pulses, the number of pulses produced depending upon the degree of rotation of said dial, a movable finger stop arranged adjacent one position on the periphery of said dial and adapted to stop the finger rotating the dial from passing said position, and pulse-responsive means for moving said finger stop to different positions adjacent the periphery of the dial in accordance with the number of pulses received thereby; a pulse-responsive controlled device; and means for transmitting pulses from said pulse-producing means to said controlled device and the finger-stop moving means.

4. A remote control system for controlling a governed instrument by a remotely-located, manually-operated, pulse-generating governing instrument, said governing instrument comprising a manually-rotatable self-returning dial, the degree of rotation thereof determining the number of pulses generated thereby, means associated with said dial indicating a plurality of positions thereon, a movable finger stop associated with said dial, the amount of manual rotation of said dial from any of said positions being limited by the position of the finger stop, pulse-responsive means for moving said finger stop adjacent different ones of said positions according to the number of pulses received, said governed instrument being likewise responsive to pulses, and means for transmitting the pulses from the governing instrument to the governed instrument and to the finger-stop moving means.

5. A remote control system according to claim 4 wherein said governed instrument includes a continuously rotatable member adapted to rotate through as many different positions as said dial, and a stepping relay arranged to rotate said member to advance it a single position for each pulse applied to said stepping relay.

6. A remote control system according to claim 4 wherein said governed instrument includes a continuously rotatable member adapted to rotate through as many different positions as said dial and a stepping relay arranged to rotate said member to advance it a single position for each pulse received, and said means for moving said finger stop includes a second stepping relay in series with said first stepping relay, said second stepping relay being arranged to advance said finger stop a single position for each pulse.

7. A remote control system according to claim 4, wherein said transmitting means consists solely of a single conductive line and return.
